FIG. IV

FOLIO V

UNITED STATES PATENT OFFICE.

ALBERT M. PIGEON, OF NORRISTOWN, PENNSYLVANIA, ASSIGNOR TO WILDMAN MFG. CO., OF NORRISTOWN, PENNSYLVANIA, A CORPORATION OF PENNSYLVANIA.

KNITTING-MACHINE.

1,321,472.

Specification of Letters Patent. Patented Nov. 11, 1919.

Application filed October 4, 1917. Serial No. 194,666.

To all whom it may concern:

Be it known that I, ALBERT M. PIGEON, of Norristown, in the county of Montgomery and State of Pennsylvania, have 5 invented certain new and useful Improvements in Knitting-Machines, whereof the following is a specification, reference being had to the accompanying drawings.

The invention relates more particularly 10 to a spring beard knitting machine, having a needle cylinder which is at times continuously rotated for ordinary tubular knitting and at times oscillated for knitting heel or toe pockets, or the like. For convenience 15 of description I shall refer to the two operations as "rotary knitting" and "oscillatory knitting."

In my co-pending application, Serial No. 633,938, filed June 19, 1911, Patent No. 20 1,266,044, May 14, 1918, I have shown and described a knitting machine on which the present machine is an improvement. In said prior application the yarn, fed to the needles, rests on yarn-supporters which 25 serve as means for positively holding the yarn above, and for definitely spacing it from the last preceding course of the knit fabric, so as to allow the beard of the needle to descend well past the supported yarn, 30 before the beard depressor closes the beard. The yarn-supporters of my co-pending application furthermore serve as holders for the knitted web, to prevent it from rising when the needles move upward, and also 35 afford definite horizontal surfaces against which the descending needles may draw off the new loop of yarn, and thus, by the extent of their downward movement, determine the length of the loops, without the employment 40 of sinkers.

An object of the present invention is to provide controlling means for insuring a peculiar position of the yarn-supporters with respect to the needles, at certain critical periods.

A further object of the invention is to combine a pattern mechanism with controlling means of the above character, whereby the position of the yarn-supporters, with 50 relation to the needles at said periods, may be properly accommodated to the conditions when the change is made from oscillatory knitting to rotary knitting, or vice versa.

These and other objects will be herein- 55 after more fully described.

In the drawings, Figure I, is a perspective view of a portion of a knitting machine, having my improvements applied thereto in a preferred form.

Fig. II, is a partial plan view of the 60 needle cylinder, the yarn-supporters, the cam ring and the operative parts supported thereby.

Fig. III, is an inverted plan view of the cam ring for the actuation of the yarn- 65 supporters.

Fig. IV, is an enlarged diagrammatic view, showing the relation of one of the yarn-supporters to a co-acting needle at the time when, during oscillatory knitting, said 70 needle is descending and is about to draw the yarn (inclosed in its bight) past the tip of the yarn-supporter.

Fig. V, is a similar view of said parts at the corresponding moment during rotary 75 knitting.

Fig. VI, is a detail view in vertical cross section on the line VI, VI, of Fig. II.

Fig. VII, is a diagrammatic plan showing three adjacent needles and two intermediate 80 yarn-supporters in the position corresponding to that shown in Fig. IV, i. e., at the time when the descending needles have engaged the yarn within their bights and are about to snap it off from the tip of the yarn- 85 supporter, in oscillatory knitting.

Fig. VIII, is a diagrammatic plan view of said parts showing the position of the 90 yarn-supporters at the corresponding time during rotary knitting.

In carrying out my invention, I employ a knitting machine having a needle cylinder and actuating devices for rotating or oscillating it. The needles are of the spring-beard type, and each of them in the instance 95 shown, is provided with an individual beard-depressor, mounted in the groove of the needle cylinder and actuated by cams of the usual character. The machine is also provided with yarn-supporters which extend horizontally between the needles. These 100 yarn-supporters may be of the general type shown and described in my said co-pending application, that is to say, each is provided with a fabric-supporting lower ledge and a yarn-supporting upper ledge, the tip or inner extremity of which latter overhangs a portion of the fabric-supporting ledge, with an intervening notch, in which the previously formed fabric is en- 110

gaged, so that it is prevented from rising with the needles. The yarn-supporters are mounted and guided in radial grooves formed in the top of the needle cylinder, 5 and are spring-pressed inwardly (or toward the needles), the extent of their inward projection being limited by the wall of a cam race, which is provided at certain regions, with outwardly projecting cam-in- 10 cliners, or acting faces whereby the yarn-supporters are withdrawn positively outward at corresponding points of the travel of the needle cylinder, said race being formed in a stationary cam-ring, which sur- 15 rounds the upper extremity of the needle cylinder.

During the greater portion of the needle cylinder's travel, the yarn-supporters are protruded to their extreme inward position, 20 corresponding to what may be considered as the normal wall of the race, and the withdrawing cam surfaces are three in number, located symmetrically in the following manner: One is immediately opposite to the 25 yarn guide. The other two are respectively adjacent to the knitting cams, and are, therefore, located at a short distance from, and on either side of, the yarn guide.

During both rotary and oscillatory knitting all three of these sets of cams are, of course, physically active, but only one of them is functionally operative during rotary knitting, *i.e.*, the one which is adjacent to the then active knitting cams, the movement of the yarn-supporters by the other two sets of yarn-supporter cams being an idle one.

During oscillatory knitting, however, all three sets of these cams are functionally 40 operative.

As above stated, an important function of the yarn-supporter is due to the fact that its ledge maintains the newly fed yarn in proper position, spaced vertically above, 45 but at a definite distance from the last previously formed series of the fabric loops, this support continuing during a period which allows ample time for the passage of the point of the needle beard down over the 50 yarn and the closure of the beard before the new yarn inclosed by it is drawn down through the previously formed loop then upon the shank of the needle. For the proper performance of this function, the 55 yarn-supporter must protrude to a substantial distance within the needle circle, but it must be withdrawn to the required degree at the period of ultimate descent of the needle in order to permit the yarn bight in- 60 closed by the needle to be drawn down through the previously formed loop.

In continuous rotary knitting it is desirable that the yarn-supporter should not protrude substantially within the needle circle 65 at the moment when the yarn is to be drawn

down past the tip of the yarn-supporter. In stocking manufacture this condition of course corresponds to the period of formation of the leg. The leg portion of the stocking is usually knit of a very fine gage 70 yarn, hence it is essential that the yarn be subjected to the least possible tensile strain in the feeding of the same to the needles. When the yarn supporters are positioned so as not to protrude substantially within the 75 needle circle during rotating knitting, then, of course, the yarn will slip from the yarn supporters without being bent so as to subject the same to any great tensile strain. On the other hand, during the formation of 80 the heel and toe pockets, and consequently during the period of oscillatory knitting, a slight protrusion of the yarn-supporter tip within the needle circle is found highly useful. In knitting the heel and toe pockets, 85 a yarn of heavier gage is employed, so that the snapping action on the yarn attending the feeding has no injurious strain on the yarn and, therefore, the yarn supporters may be positioned so as to protrude 90 within the needle circle. This insures the positive support of the yarn and also prevents it being dragged under the yarn-supporting tips by the terminal needle of the active series and trapped by the yarn sup- 95 porter tips and the elevated inoperative needles during oscillatory knitting. To this end I provide by my present invention means whereby the radial protrusion of the yarn-supporters at the region of that set of 100 knitting cams which is functionally operative during rotary knitting, may be varied, so that the yarn-supporters may be withdrawn to a greater extent, at the knitting point, during rotary knitting, and to a less 105 extent during oscillatory knitting.

As above stated, those cam surfaces for the yarn-supporters, which correspond to the position of the second set of knitting cams, though physically active, are functionally idle during rotary knitting, and, therefore, may, if desired, be made permanently of the desired radial extent for proper operation of the yarn-supporter during the period of oscillatory knitting. The 110 third set of cam surfaces which correspond to the position of the yarn guide, and which may be considered as functionally idle during rotary knitting, should be of such depth as to withdraw the yarn-supporter tip entirely clear of the needle circle at the time of passage by the yarn guide, in order to prevent the danger of trapping of the yarn by the yarn-supporter tip at the passage of that point during the period of oscillatory 115 knitting.

Referring to the drawings, I have shown my improvements applied to a circular knitting machine, which includes a needle cylinder 1, having a series of spring-beard needles 120

2. The needle cylinder is mounted in a bed plate 3, and is provided with suitable mechanism for rotating, or oscillating it, this mechanism being controlled by pattern 5 mechanism in any well known way. The yarn guide for the main yarn y , has a delivery eye 28, situated at a relatively low level with respect to the needles. The knitting cams for raising or lowering the needles 10 are of the usual construction, and I have not, therefore, shown the same in the drawings. The spring-beard needles are provided with needle-butts, and these are operated upon by suitable pickers, the lowering picker mechanism being shown at 4, in Fig. I, the raising cam at 5, and the lowering cam at 6. The clutch for shifting from circular knitting to oscillatory knitting, or vice versa, is controlled by a rod 7. Co-operating 15 with each needle is a beard-depresser 8, see Fig. VI. These beard-depressors are operated by means of cams 9, and 10, mounted on the stationary cam ring 11, at the region of the respective knitting cams. Each 20 beard-depressor cam is formed with slots such as 12, and 13, through which guiding screws 14, extend. The beard-depressing cams are pressed radially inward, by means of springs 15, the range of their inward 25 movement being limited by stop screws 16.

Extending between the needles are the 30 yarn-supporters 17, there being a yarn-supporter between each two adjacent needles. These yarn supporters are carried and guided 35 in radial slots formed in the ring 18, which surrounds, and is mounted upon, the upper end of the needle cylinder. Each yarn-supporter comprises, at what may be termed its front portion, a fabric supporting ledge 40 19, and a yarn supporting ledge 20, located above the ledge 19, and having a projecting tip portion 21, which overhangs the fabric supporting ledge, with an intervening notch, in which the upper edge of the fabric 45 engages, so as to be prevented from rising with the needles. The rear portion of the yarn-supporter is provided with an upwardly projecting butt 24, adapted to cooperate with cam surfaces. The yarn-supporters 50 are mounted so as to move independently of each other, and are moved radially inward, or protruded, by means of the spring 22, which embraces and presses against their rear extremities. The inward movement, or protrusion, of the yarn-supporters 55 is limited, and their outward movement, or withdrawal, is effected, by means of cam devices, which are shown in inverted position in Fig. III.

60 A stationary cam ring 11, extends around the upper portion of the needle cylinder and overhangs the rear portion of the yarn-supporters. Said ring is provided with a cam race whose walls depend downwardly 65 and are adapted to receive between them the butts 24, of the yarn-supporters. The inner wall of said race determines the degree of protrusion of the yarn-supporters, and throughout the greater part of its extent, (including the broken away portion of 70 Fig. III), said wall is circular, as indicated at 23. The normally circular wall is, however, provided with three cam inclines, situated at 25, 26, and 27, respectively, for effecting the withdrawal of the yarn-supporters 75 in an outward direction. The inclines at 25, and 27, may be adjustably mounted in the usual manner, but are preferably maintained in an unvarying position, when properly adjusted in position for any given yarn. The 80 incline at 26, is part of a normally movable section 32, pivotally mounted at one extremity upon the pivot 33, so that the radial distance of its outer surface, from the axis of revolution of the yarn-supporters, 85 may be immediately varied by shifting said section. The devices for shifting the section 32, will be described later on, it being considered important at this point to explain the action of the cams. 90

During rotary knitting, the movement of the needle cylinder is in the direction of the arrow shown in Fig. II, and the knitting is effected by the knitting cams located at the region corresponding to the beard depressor cam 10, which is the one toward the right in Fig. II. Hence, (since the view of the cam race in Fig. III, is inverted) the withdrawal of the yarn-supporters at this knitting point is effected by the cam incline 95 at 26. During rotary knitting, the cam inclines at 25, and 27, though physically acting upon the yarn-supporter butts, are, as before stated, functionally idle. When said cam incline 26, is in its outermost position, 100 the radial distance of its operative surface is similar to that of the constant radial distance of the incline at 27. The successive positions of the tips when the incline at 26, is in its outermost position, are indicated graphically by the contour of the solid line s , in Fig. III, and this solid line is therefore characteristic of the positions of the yarn-supporters during rotary knitting. 105 When, however, oscillatory knitting is being performed, the cam incline at 26, is swung to its innermost radial position, indicated by the dotted lines in Fig. III, and consequently, the position of the tips of the yarn-supporters as the latter pass this incline, is indicated by the short dotted portion s' of the line s . It will be understood, of course, that the yarn supporters are yieldingly forced outwardly and the cam inclines 25, 26, and 27 are limiting cams, so 110 that when the cam incline 26 is in the full line position in Fig. 3 for rotating knitting, the tips of the yarn supporters do not protrude within the needle circuit, while when the cam is in the dotted line position shown 115 120 125 130

in this figure, then the tips of the yarn supporters will be pressed farther toward the center of the needle cylinder and will protrude beyond the needle circle and this is 5 during oscillating knitting.

Referring now to Figs. VII and VIII, I have illustrated diagrammatically and on an enlarged scale, the general relations of the yarn-supporter tips, the needles and the 10 yarn. Thus, in Fig. VII, the position of the yarn-supporter in oscillatory knitting at the moment corresponding to the descent of the needles 2, carrying the yarn y^2 , past the tips, is shown. It will be noted that the 15 tips of the yarn-supporters 17, extend in part-way between the needles, and that the yarn y^2 , rests upon them at the moment of its descent with the needle, so that there is a slight momentary indentation and 20 stretching of the yarn between the needles, due to the fact that it has to be snapped off from the tips.

Referring now to Fig. VIII, where the 25 position of the corresponding moment in rotary knitting is shown, it will be seen that the tips of the yarn-supporters 17, are completely withdrawn from the needle circle so as to be clear of the yarn. This 30 position is also characteristic of the moment when the yarn-supporters pass by the yarn guide, corresponding to the region of the cam incline 27. It will be noted that the 35 yarn is delivered to the needles from the yarn guide 28, at a comparatively low feed-ing point, and close to the needle cylinder, so that the yarn is wrapped about the outer 40 faces of the series of needles at a comparatively obtuse angle to the axis of the cylinder, and rests upon the shelf formed by the 45 series of yarn-supporting ledges 20. The holding of the yarn in a definite and approximately horizontal position on the shelf of yarn supporters during the descent of the needles until the beards have passed over the yarn and are in a position to be 50 depressed, is very important for positively insuring the feed of the yarn to the needles. After the needles have received the yarn under the beards and the same have been 55 pressed, the complete withdrawal of the yarn supporters is desirable so that the yarn is not bent and required to be snapped off the yarn supporter tips. In oscillatory knitting as for heel and toe pockets, the 60 protrusion of the yarn supporter tips so as to bend the yarn is very important, so as to prevent the yarn being dragged under the yarn supporter tips by the terminal needle of the active series and be trapped 65 by the yarn supporter tips and the elevated inoperative needles. It will be understood that when the needle cylinder is oscillated, that it is essential to hold the yarn well supported relative to the terminal needle of the active series. By this holding of the

yarn supporters well forward, at the critical point in the change of the direction of movement of the needle cylinder relative to the feed of the yarn, this supporting of the yarn is accomplished and, as above 70 noted, the yarn is prevented from being dragged under the yarn supporter and trapped by said yarn supporter tips and the elevated inoperative needles.

The mechanism whereby the radial position of the cam incline at 26, may be varied is as follows: The section 32, which carries the cam-incline 26, and which is pivotally mounted at 33, is engaged by a pin 36, (see Fig. VI), which is rigidly secured to the 75 end of a lever 35, and projects down through an opening 37, in the cam ring, and into an opening in the movable section 32. The lever 35, which is fulcrumed at 38, on the top of the cam ring 11, (see Fig. II) 80 projects outwardly beyond the cam ring, and its free end 39, is adapted to be engaged by an arm 40, carried by a bracket 41, which is fixed to an arm 42, secured to the rod 7, which controls the clutch for shifting from 85 circular knitting to oscillatory knitting, and vice versa. This bracket also carries the controlling finger 43, for one of the pickers, and a controlling finger 44, for the raising and lowering cams. The arm 40, is adapted to engage the angular end portion 39, of 90 the lever 35, when the slide rod 7 is moved in, and this occurs when the clutch is shifted so as to cause the needle cylinder to rotate for circular knitting. An adjustable 95 stop 45, limits the inward movement of the lever 35. The arm 40, while slightly flexible, is sufficiently rigid to prevent the 100 spring which tends to move the yarn supporters inward toward the center of the cylinder, from moving the lever 35, also, unless a jamming should occur, in which case the arm 40, can yield sufficiently to prevent breakage. For operative purposes, 105 however, the arm 40, cooperates with the lever 35, so as to move the end thereof attached to the section 32, outwardly, and this swings the section 32, on its pivot so as to 110 reposition the projecting cam incline 26.

The wall of the opening 37, limits the 115 movement of the pin 36, through the action of the spring 22, of the yarn-supporters when the arm 40, is moved away from the lever 35.

It will be noted that I have provided 120 means whereby the degree of the withdrawal of the yarn-supporters may be immediately varied according to the conditions desirable for rotary knitting and oscillatory knitting respectively. This mode of 125 operation is irrespective of the feature of general adjustability of the yarn-supporter cams, at what may be considered as normally permanent radial distances, in order to accommodate yarns of different weights 130

or gages, or a plurality of yarns. Thus, a splicing yarn indicated at y' , may be used, said yarn being delivered by the yarn guide 29, or yarns of different gages may be employed, the drawing down of which, without undue tension, especially during rotary knitting, may require different adjustments of the yarn-supporter.

During the knitting of the heel and toe 10 pockets other yarns, indicated at y^2 , and y^3 , may be employed, being respectively delivered from suitable guides 30, and 31.

These several yarn guides may be thrown 15 into or out of operation by suitable pattern mechanism, such as is well known in this class of machines, but to produce the best results, the delivery point of said guides, when in operative position, should be at a relatively low level and close to the needles.

20 In the foregoing specification I have described the employment of an individual beard-depressor for each needle, but it must be understood that this is merely a preferred construction. Furthermore, while in 25 the instance set forth the yarn-supporters are described as spring pressed inwardly, such method of actuation is not essential to my invention.

Having thus described my invention, I 30 claim:

1. A knitting machine including in combination, a needle cylinder, knitting cams, means for effecting the relative movement of said cylinder and cams, spring beard 35 needles carried by said cylinder, means to depress the needle beards, yarn supporters for supporting and positioning the yarn while the beards of the needles are descending past the same, means for rotating the 40 needle cylinder for plain knitting and for oscillating the cylinder for oscillating knitting, means for protruding and withdrawing the yarn supporters in correlation with the knitting action, and means for varying the 45 extent of withdrawal of the yarn supporters with respect to the needles when changing from rotating to oscillating knitting.

2. A knitting machine including in combination, a needle cylinder, knitting cams, 50 means for effecting the relative movement of said cylinder and cams, spring beard needles carried by said cylinder, means for depressing the needle beards, yarn supporters for supporting and positioning the yarn while 55 the beards of the needles are descending past the same, means for rotating the needle cylinder for plain knitting and for oscillating the cylinder for oscillating knitting, means for protruding and withdrawing the 60 yarn supporters in correlation with the knitting action, means for withdrawing the yarn supporters to a greater extent for rotating knitting than for oscillating knitting.

3. A knitting machine including in combination, a needle cylinder, knitting cams,

means for effecting the relative movement of said cylinder and cams, spring beard needles carried by said cylinder, means to depress the needle beards, yarn supporters for supporting and positioning the yarn 70 while the beards of the needles are descending past the same, means for rotating the needle cylinder for plain knitting and for oscillating the cylinder for oscillating knitting, yielding means for protruding the 75 yarn supporters in correlation with the knitting action and cam inclines for withdrawing the yarn supporters in correlation with the knitting action, and means for varying the position of the cam inclines acting upon 80 the yarn supporters when changing from rotating knitting to oscillating knitting.

4. A knitting machine including, in combination, a needle cylinder; means adapted to rotate it for plain tubular knitting, and 85 to oscillate it for the production of heel and toe pockets; knitting cams; spring beard needles carried by the cylinders; means to depress the needle-beards; yarn-supporters extending between adjacent needles; means 90 for protruding and withdrawing said yarn-supporters, including means whereby the tips of the yarn-supporters are protruded within the needle circle at the region of the knitting point, during oscillatory knitting, 95 and are withdrawn from the needle circle at the knitting point during rotary knitting.

5. A knitting machine including, in combination, a needle cylinder; means adapted to rotate and to oscillate said cylinder; knitting cams; spring beard needles carried by the cylinder; means to depress the needle-beards; yarn-supporters extending between adjacent needles; an actuating cam for said 100 yarn-supporters, said cam including a pivotally mounted section for immediately varying the extent of withdrawal of the yarn-supporters at the region of a knitting point when changing from rotating to oscillating movement of the cylinder; and means 110 for swinging said section.

6. A knitting machine including, in combination, a needle cylinder; knitting cams; means for rotating and for oscillating said cylinder, said means including clutch mechanism for changing the character of movement; spring beard needles carried by the cylinder; means to depress the needle beards; yarn-supporters extending between adjacent needles; devices for independently 115 moving said yarn-supporters radially with relation to the needle circle, said devices including a sectional cam for immediately varying the radial position of the yarn-supporters, at the region of the knitting point which is operative during rotary knitting; and means for operatively connecting said sectional cam to the clutch shifting mechanism for changing from rotary to oscillatory knitting, whereby the yarn-sup- 120 125 130

porters may be automatically caused to protrude a less distance with relation to the needle circle at said knitting point during circular knitting, than during oscillatory knitting.

5 In testimony whereof, I have hereunto

signed my name at Norristown, Penna., this first day of October, 1917.
